UNITED STATES PATENT OFFICE.

CHARLES WM. SMITH, OF WOODLAWN, PENNSYLVANIA.

DIAMOND-SHAPED BOX.

BEST AVAILABLE COPY

1,322,637.

Specification of Letters Patent. Patented Nov. 25, 1919.

Application filed June 1, 1918. Serial No. 237,756.

To all whom it may concern:

Be it known that I, CHARLES WILLIAM SMITH, a citizen of the United States, residing at Woodlawn, in the county of Beaver 5 and State of Pennsylvania, have invented new and useful Improvements in Diamond-Shaped Boxes, of which the following is a specification.

This invention relates to diamond shaped 10 boxes and particularly to the means for locking and folding the ends thereof and it consists in the novel features hereinafter described and claimed.

An object of the invention is to provide a 15 box of simple and durable structure the same consisting of a blank foldable so that the box is rhomb-shaped or diamond shaped in transverse section. Another object of the invention is to provide means for effectually 20 closing and sealing the end portions of the box.

With these objects in view the invention consists in providing the blank with sections 25 adapted to form the sides of the box and having tongues adapted to close the ends thereof, and suitable flanges for binding the tongues and for holding the sides of the box in position.

In the accompanying drawing:

30 Figure 1 is a plan view of the blank from which the box is formed.

The other figures are detailed views of the features of the invention.

As illustrated in the accompanying drawing 35 the blank is cut from a single sheet of material as for instance heavy paper and includes sections 1, 2, 3, 4, and 5 the said sections being defined with relation to each other by means of scorings or folds in a 40 usual manner.

The section 1 is provided at one end with a triangular tongue 6 and at its opposite end with a quadrilateral tongue 10. The section 2 is provided at one end only with a rhomb 45 shaped tongue 7 having at its outer edge a lip 9. The section 3 is provided at one end with a quadrilateral tongue 8 and at its other end with a triangular tongue 11. The

section 4 is provided at one end only with a rhomb shaped tongue 12 having at its 50 outer edge a lip 13. The tongues 6, 7 and 8 are located at the opposite sides of the blank from the tongues 10, 11, and 12. The tongue 6 corresponds in shape and dimension with the tongue 11. The tongue 10 corresponds in shape and dimension with the tongue 8. The tongue 7 corresponds in shape and dimension with the tongue 12.

When the blank is folded to form the box the sections 1, 2, 3, and 4 are disposed 60 at angles with relation to each other and the section 5 is attached to the section 1 by using an adhesive or other means. The tongues 6 and 8 are folded in at one end of the box and the tongues 10 and 11 are 65 folded in at the other end of the box then the tongue 7 is folded over the tongues 6 and 8 and the tongue 12 is folded over the tongues 10 and 11 whereby the body of the box of which the sections 1, 2, 3, and 4 are 70 the sides, will assume the shape of a rhomb in transverse section. The lips 9 and 13 are then inserted between the adjacent sides of the box and the edges of the adjacent tongues and consequently the ends of the 75 box are closed and sealed.

From the foregoing description taken in conjunction with the accompanying drawing it will be seen that a diamond shaped box 80 of simple and durable structure is provided and that the box may be easily and quickly formed by folding or bending the blank as hereinbefore described.

Having described the invention what is 85 claimed is:

A blank for a box comprising four connected sections, two of the sections having at one end triangular shaped tongues and at their other end quadrilateral tongues, the other two sections being provided at one end only with rhomb shaped tongues and lips provided at the outer portions of the rhomb shaped tongues.

In testimony whereof I affix my signature.

CHARLES WM. SMITH.
